CASTER

Lester C. Rogers, Cleveland, Ohio, assignor of
one-half to Alex Gould, East Cleveland,
Ohio

Application April 27, 1938, Serial No. 204,652

4 Claims. (Cl. 16—30)

This invention relates to casters.

It is an object of this invention to provide casters constructed to embrace and be frictionally attached to the legs of refrigerators, furniture and the like.

A further object is to provide casters designed to frictionally embrace the legs of refrigerators, furniture and the like and adapted for application to legs of varying thickness.

10 A further object is to provide casters formed of sheet metal, characterized by simplicity of construction, low cost and ease of application and removal. Other objects of the invention will become clear as the description thereof proceeds.

15 In the drawing forming part of this specification:

Figure 1 is a partial elevation of a lower corner of a refrigerator showing a caster of the invention applied to one leg of the refrigerator.

20 Figure 2 is a horizontal section taken on line 2—2 of Figure 1.

Figure 3 is an elevation of the caster shown in Figure 1.

Figure 4 is a plan view of the caster.

25 Figure 5 is a vertical section taken on line 5—5 of Figure 3.

In the drawing, I have illustrated a preferred embodiment of my invention as applied to a leg of a refrigerator. This illustration is illustrative only, it being understood that my novel caster may be applied to the legs of other articles as well.

30 In its preferred embodiment the caster is constructed of an attaching member designated in its entirety by the reference numeral 10. This attaching member is preferably formed of sheet metal, such as sheet steel, fabricated so as to provide a base 11, spaced upwardly extending flanges 12—12 and an upwardly extending flange 13 offset from the spaced flanges 12—12. All of these flanges are preferably integral with the base 11 of the attaching member.

35 It will be observed from the drawing that the flanges 12—12 and 13 are triangularly related so that the flanges 12—12 may be disposed in engagement with the outer face of the angular leg 14 of the refrigerator 15 and be conformed therewith. It will be understood, of course, that the contour of the flanges 12—12 may be modified 40 in order to adapt them for engagement with legs of correspondingly varying contours and that these flanges may be finished so as to agree with the finish of the legs. In the described relationship between the flanges 12—12 with the leg of the refrigerator the upstanding flange 13 is dis-

posed inwardly and in spaced relation to the inner face of the leg 14.

In the application of my caster to a leg of a refrigerator or the like, the attaching member 10 of the caster is applied to the leg until the base 11 is engaged with the lower edge of the leg. In this position contact is obtained between the spaced flanges 12—12 and the outer face of the leg 14. Thereupon the inner upstanding flange 13 is bent downwardly into engagement with the inner face of the angular leg 14 of the refrigerator, thereby securely and frictionally attaching the caster to the leg.

45 To the base 11 of the attaching member 10 there is secured a roller 16, such attachment being effected by means of riveting or welding as desired.

50 It will be clear from the hereinbefore described construction of my novel caster and of the mode of attachment thereof that it possesses an inherent adjustability by virtue of which it may be attached to legs of varying thickness without necessitating modification of the caster. It will be apparent, moreover, that should it be desired to remove a caster from a leg, such removal may be effected easily and quickly.

55 It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A device of the character described comprising a sheet metal member embodying a base, integral flanges extending upwardly from said base adapted to engage the outer face of a leg of a refrigerator or the like, and an integral flange initially extending upwardly from said base in spaced relation to said first mentioned flanges, said last mentioned flange being folded downwardly against the inner face of said leg subsequent to the application of said device to fasten said device to said leg, there being a roller secured to said base and extending downwardly therefrom.

2. A caster for refrigerators, furniture and the like comprising a base, a plurality of angularly related substantially vertical flanges extending from said base, one of said initially vertical flanges being folded downwardly toward the remaining flange subsequent to the application of said caster to provide therewith frictional embracing means for securing said caster in position

and a roller secured to and extending from said base.

3. A caster for refrigerators, furniture and the like comprising a base, a plurality of angularly related flanges extending upwardly from said base and a flange initially extending upwardly from said base disposed rearwardly of and substantially midway between said angularly related flanges, said last mentioned flange being folded downwardly toward said angularly related flanges subsequent to the application of said caster for the purpose set forth.

4. A device of the character described comprising a metallic member embodying a base, flanges extending upwardly from said base adapted to engage the outer face of a leg of a refrigerator or the like and a flange initially extending upwardly from said base in spaced relation to said first-mentioned flanges, said last-mentioned flange being folded downwardly against the inner face of said leg subsequent to the application of said device to fasten said device to said leg, said downwardly folded flange being bowed upwardly. 10

LESTER C. ROGERS.
